UNITED STATES PATENT OFFICE

ALBERT M. FARMER, OF DETROIT, MICHIGAN, ASSIGNOR, BY MESNE ASSIGNMENTS, TO THE FARFALL COMPANY, OF DETROIT, MICHIGAN, A CORPORATION OF MICHIGAN

PUMP FOR LUBRICATING SYSTEMS

Application filed October 15, 1928. Serial No. 312,577.

This invention relates to a lubricating system for effecting the delivery, by the single actuation of a piston or other fluid-advancing part, of masses of lubricant projected through the pipes of a unitary system, for contemporaneous delivery to a plurality of different bearings or other parts to be lubricated, and has for its object an improved organization of parts adapted to obviate some of the objections to apparatus of this kind which have heretofore prevailed, particularly in the direction of making allowances for variant grades of lubricant, and of securing quick and easy access to the piston and plunger parts without disassembly of the whole structure. Functioning with the parts here particularly described are preferably certain valves and other controlling media appurtenant more particularly to the delivery line itself, the details of certain preferred forms of which form the subject of now co-pending applications for patent filed by me and consequently necessary to be mentioned here only casually.

25 In the drawings:

Figure 1 is a sectional elevational view of one form of the storage vessel and of the plunger and its associated parts.

Figure 2 is an end elevational view of this 30 form of device taken from the right hand end as shown in Figure 1.

Figure 3 is a partly sectional elevational view of a slightly modified form of device taken from the same position as Figure 2.

35 Figure 4 is an enlarged sectional detailed view taken along the line 4-4 of Figure 1 and looking in the direction of the arrows there shown.

Figure 5 is a side elevation of a slightly 40 modified form of device wherein a screw-actuated piston is substituted for the spring retracted piston shown in Figure 1, and a variant though functionally equivalent venting arrangement is provided.

45 Figure 6 is an end elevational view of the modified form shown in Figure 5.

Figure 7 is a detail perspective of the lubricant-controlling plunger disassociated from the other parts.

50 Figure 8 is a perspective of one of the ter-

55 minal bounding and regulating nuts for the plunger shown in Figure 7.

Referring first to the form of device illustrated in Figures 1, 2, and 3, A indicates a tank or fluid receptacle, provided with a removable cap A' and preferably with a strainer A², the receptacle being designed to be supported from a wall or vehicle chassis by some such means as the bolt A³ passing through the wall thereof. A channel or passage B leads from the bottom of the tank A into a horizontal bore or passage C, in the base block E. As brought out in Figure 3, this bore B which continues in a horizontal direction as the branch D, of a flattened or slotted cross section, and leads to connection at D' with the chamber F wherein the piston G engages, the latter being yieldingly held in projected position by the spring H, so that when the piston G is forced inwardly by 70 manual or other pressure upon the handle G', the spring H is placed under compressive strain. One end of the spring H of course engages against one end of the piston G, whereas the other end rests upon the headed 75 end of the centrally apertured nut J, which, except for said aperture, closes the left hand end of the bore C as viewed in Figure 1.

80 Centrally of the bore C the plunger K slidably engages, and when it occupies the position shown in Figure 1 in full lines, it closes the passage B from the storage chamber A. When, however, it is suctionally moved, as hereinafter described, to the dotted-line position shown in Figure 1, its groove K' so registers with the bore B as to permit the flow of fluid therethrough to the horizontal passage D. The end of bore C is closed by the removable nut L, and extending obliquely upward from that end of the bore C 85 adjacent the nut L to communication with the chamber A is a vent passage L'. Below the intersection of the passage B with the flattened bore D, the bore M extends further downwardly to communication with the lubricant-distributing line M', in which is conveniently positioned a suitable valve, as M², for protecting the apparatus against back pressure of the lubricant previously fed into the line when there is a suction condition in- 100

duced within the apparatus here dealt with, as will hereafter be described.

It will be noted that whereas the device shown in Figures 1 and 2 is illustrated as unitary, in that a web or neck A⁴ connects the supply or storage chamber with the piston and bored parts, in the form shown in Figure 3, a union is had between the storage shell and the lower bored body E by means of the bolts N which pass through suitably flanged portions N' of the respective shells, thus making disassembly of the device possible without interference with the assembly of the parts contained within the bored body E.

In the form of device shown in Figures 5 and 6, a slightly variant form of tank or container is shown at O, united by a web O' to the piston and bore body P. If desired, this latter may be made in two parts, the piston cylinder P' being united to the bore and plunger portion of the mechanism by bolts P² passing through flanges P³. The elbowed bore Q which corresponds in function of the bore D in the form shown in Figures 1 and 2, leads, when the plunger R is in suitable position, from connection with the bore T, through which the lubricant proceeds from the storage chamber O into the chamber S, which is connected with the plunger bore U through the hole V' in the nut V, similarly to the functioning of the nut J in the device shown in Figures 1 and 2. The lubricant-projecting piston W which engages in the cylinder P' is preferably protected against end thrust as regards its connection with its stem Y by means of roller or similar bearings W'. The stem Y which is screw-threaded passes through the threaded end of the cylinder P', and rotative actuation of the stem, for effecting the projection or retraction of the piston W, is effected manually upon the handle or spider Y².

The operation of this device is as follows: Referring first to the form shown in Figures 1, 2, and 3, when, due to the positioning of the plunger K within its bore C so that the groove K' is in registry with the vertical bore B, lubricant has been allowed to pass from the storage chamber A down through the bore B and the horizontal, flattened bore D into the chamber F, the device is ready for inward actuation of the piston G against the spring H. The first effect of this movement of the piston is to exert a pneumatic driving influence upon the plunger K, because of the connection of its bore C with the chamber F through the central hole J' in the nut J. This effects the movement of the plunger K to the full-line position shown in Figure 1, thus closing the bore B, the oil in the space between the right hand end of the plunger K and the nut L venting into the chamber A through the channel L'. Further pressure upon the piston G now

produces a pressure upon the lubricant within the chamber F and the horizontal bore D, which must relieve itself by movement of the oil body through the delivery bore M and into the pipe line M', at different points along which the several lubricant-receiving elements are located, each preferably protected by a nipple or a suitable controlling member. Upon the cessation of pressure upon the handle G' the resilience of the spring H acts to force the piston G backwardly, thus creating a suction condition which would tend to draw out some of the lubricant already projected into the line M' but for the interposition therein of a control valve M², but with that acting to prevent the suctional withdrawal of lubricant already within the line M', the suction effect caused by the retractile movement of the piston G acts both to draw into the chamber F such quantity of lubricant as remains within the bore D and that part of the supply line M' above the valve M², and also effects a suction draw through the hole in the nut J, upon the plunger K, thus retracting it to such a position that its groove K' again registers with the feed bore B from the supply container, thus allowing the refilling of that part of the system contained within the bored body E for a similar repeated actuation of the plunger G, which of course will again effect the passage of another mass of lubricant past the valve M² in the supply line.

In the form of device shown in Figures 5 and 6, the same functioning of the parts takes place as regards the closure or opening of the bore T due to the blanking thereof by the plunger R, or the registry therewith of its annular groove R². In this case, however, in place of the oblique vent bore L' shown in Figure 1, I provide a terminal nut Z, through the central bore Z² of which the oil projected by the advancing movement of the plunger R (to the left in the position here shown) may be vented directly to the atmosphere. In this case, however, it is desirable that a bevelled valve seat Z' be formed in the end of the nut Z for engagement by the correspondingly contoured end R' of the plunger R, so that when lubricant is passing through the feed bore T and past the groove R² in the plunger R, no leakage thereof may occur through and past this nut-closed end of the bore U. The projection of the lubricant is, in this form, effected by the screw-advanced movement of the piston W through the space S and toward the apertured nut V. Whatever number of turns may be thought necessary are given to the actuating stem Y of the piston W and the pressure conditions upon the trapped lubricant thus induced result in a flow thereof through the supply line Q' and past its valve Q² in the same manner as already described as to the

form shown in Figures 1 and 2. Similarly the suction conditions upon the system, including the plunger R, induced by a retractile movement of the piston W effect the same refilling of the parts as have already been described as to the apparatus shown in Figures 1 and 2. The vent W² prevents the creation of a vacuum condition within the cylinder P' during the forward movement of the piston W.

It will be noted that the inner end of the centrally apertured nut J is shown as squared, as at J'. The purpose of this is to make possible its adjusted projection or retraction along the bore C, in which the plunger K engages, so that for example if it is sufficiently retracted, the plunger K may be drawn back suctionally far enough for its groove K' to fully register with the bore B, thus permitting a maximum refilling inflow of lubricant from the supply chamber A. This would be particularly desirable if a relatively heavy, slow-flowing lubricant were used. If, however, a lighter, more freely flowing lubricant is being supplied from the chamber A, it often becomes desirable to restrict the effective size of the plunger-controlled stream through the bore B, and this may be effected by first removing the outside nut L, and the plunger K, from the bore C and inserting the squared end of a rod or wrench in the squared end J² of the nut and then rotating the latter so much further into the bore C that it halts the movement of the plunger K before its groove K has fully registered with the bore B, thus constricting the available passage accordingly.

What I claim is:

1. In a lubricating apparatus, in combination with a supply source, a plurally bored base connected therewith, an annularly grooved plunger member operatively movable within one of said bores, adapted to control the possible outflow of lubricant from said supply source, means accessible from an external point for regulating the possible degree of movement of said plunger member, a manually actuatable piston member whereby the lubricant may be forced into a connected lubricating system in measured quantities, and a spring for effecting the retractile movement of said piston member, thereby suctionally effecting the movement of said plunger member to open position with respect to its controlled bore.

2. In combination with a plurally bored base piece, a plunger member limitedly movable within one of the bores in said base, adjustable means positioned at either end of said plunger member for influencing the possible degree of movement thereof, a manually actuatable piston adapted to exert a propulsive influence through a connected system upon a predetermined quantity of lubricant previously admitted within certain bores

in said base piece, and a supply container having a discharge opening connected with one of the bores in said base piece which bore is adapted to be blanked by the pressure-induced movement of said piston, against the further escape of lubricant into the bored portions of said base piece.

3. In combination with a plurally bored body member connected with a suitable supply source, an annularly grooved plunger member adapted for limited movement lengthwise of one of said bores, thereby accordingly regulating the possible flow of lubricant from the supply source through others of said bores, and an externally actuatable piston member adapted to force a measured quantity of lubricant previously admitted past said plunger member through another of said bores and into a connected system, and means interposed between said piston and the adjacent end of said plunger member whereby the limit of possible movement of the latter within its bore may be regulated from an external point after preliminary removal thereof from its bore.

4. In a lubricating apparatus, the combination, with a base member provided with a series of interconnected bores, one of which is connected with a suitable supply source and another of which leads to connection with elements whose contemporaneous lubrication is desired, of removable end closure means appurtenant to one of said bores; an annularly grooved plunger limitedly movable within the bore between said end closure means, adapted to close or leave free another of said bores which intersect its bore, according to the position of its groove relatively to the latter, and an externally actuatable piston member whereby a measured quantity of lubricant previously admitted past said plunger may be forced toward said connection with the parts to be lubricated.

5. A measuring and propulsive unit for a plurally terminalized lubricating system, having, in combination with a body portion provided with an interconnected system of bores, one of which is connected at its end with a suitable supply source and another of which is connected with the lubricant distributing system, means positioned in one of said bores and limitedly movable lengthwise thereof whereby the reception of lubricant from the supply source, through an intersecting one of said bores may be regulated, adjustable means whereby the degree of possible travel of said last-mentioned element may be regulated, and an actuating piston operably movable within a chambered terminal portion of one of said bores whereby lubricant admitted from the supply source into the system of bores may be regulatably advanced toward the units of the lubricant distributing system, and means for effecting the actuation of said piston from an external point.

6. A lubricant-projecting mechanism, having in combination with a plurally bored body connected respectively with a supply source and with the line pipe of a distribution system, an accumulation chamber into which the lubricant may proceed from the supply source, an externally actuatable piston member operative within said accumulation chamber, whereby pressure or suction conditions 5 may be selectively set up within said accumulation chamber, a discharge passage through which lubricant from said accumulation chamber proceeds toward the connection with the line pipe, a plunger member movable within one of the bores in said body and according to the position of which relatively 10 to the supply source connection the possible travel of lubricant therefrom toward said accumulation chamber is regulated, said 15 plunger being operatively responsive to the pressure and suction conditions induced by the movement of said piston member, and means susceptible of adjustment from an outside point whereby the degree of possible 20 movement of said plunger in its bore may be 25 regulatably varied.

7. In a lubricant-feeding apparatus, the combination, with a plurally bored shell connected with a supply source and with the supply line of a distribution system, a plunger member movably located within one of the bores in position to regulate the possible flow 30 of lubricant through the bores of said shell, externally accessible means whereby the 35 possible path of travel of said plunger member within its bore may be abbreviated or lengthened, thereby influencing the degree of said plunger's potential interference with the flow of the lubricant through other bores in said shell, an accumulation chamber connected with certain of said bores, and a selectively operable piston member operatively active within said accumulation chamber 40 whereby pressure and suction conditions may be regulatably induced within said accumulation chamber and its connected bores.

In testimony whereof I sign this specification.

ALBERT M. FARMER.
